OTHER PUBLICATIONS

U.S. Appl. No. 29/453,426, filed Apr. 29, 2013, Bologna, Vittorio.

Primary Examiner — Randall Gholson*(74) Attorney, Agent, or Firm* — McDermott Will & Emery LLP(57) **CLAIM**

I claim the ornamental design for a football helmet, as shown and described.

DESCRIPTION

FIG. 1 is a perspective view of a football helmet according to the new design;

FIG. 2 is a left side view of the helmet of FIG. 1;

FIG. 3 is a right side view of the helmet of FIG. 1;

FIG. 4 is a front view of the helmet of FIG. 1;

FIG. 5 is a top view of the helmet of FIG. 1; and,

FIG. 6 is a bottom view of the helmet of FIG. 1.

Features shown in broken lines in the drawings are not part of the claim.

1 Claim, 6 Drawing Sheets(56)
